UNITED STATES PATENT OFFICE

2,252,041

FIREBOX

Lauren E. Seeley, New Haven, Conn., assignor to
 The H. B. Smith Company, Incorporated, West-
 field, Mass., a corporation of Massachusetts

Application November 15, 1938, Serial No. 240,447

2 Claims. (Cl. 122—230)

This invention relates to an improvement in fire boxes, and more particularly in fire boxes for oil burning boilers. Fire boxes and combustion chambers for oil burners are commonly constructed of refractory material or metal of various shapes and sizes, depending upon the size and type of oil burner to be used and the space available in the boiler or boiler setting. The object is to provide a heated chamber in which the oil may be vaporized, mixed with air and burned. In some instances the combustion chamber is built against the water-cooled surface of the boiler itself thus shielding such portions of the boiler in a way to prevent the large absorption of heat that would otherwise take place. The only heat absorbed is that which may be conducted through the combustion chamber to the boiler surface in contact with said chamber. The heat thus conducted is relatively small.

The primary object of this invention is to provide the combustion chamber or fire box with a plurality of passages on the back side next to the boiler surface, which passages lead to a horizontal flue passage beneath the hearth or bottom of the fire box, said passage communicating in a suitable manner with the smoke pipe. Thus a means is provided whereby a certain fraction or all of the flue gases may descend through the plurality of passages, giving up heat to the boiler surface that is commonly shielded and inaccessible to the hot flue gases. The result is a more efficient use of the boiler heating surface with higher capacities and efficiencies than otherwise would be possible. This arrangement may also reduce draft requirements and exert a beneficial effect upon oil burners which are inclined to pulsate. The above must be considered as collateral advantages depending upon design of the remainder of the boiler and the tendency of the oil burner to pulsate. The invention is not a specific remedy for pulsation but is helpful in many cases. The improved use of boiler heating surface is definitely achieved by this invention. Where boiler heating surface does not lie behind the fire box, the invention has no application. The plurality of passages may be formed by grooving the walls of the chamber to form continuous passageways, by forming passageways through the walls of the chambers or fire box or in the boiler itself or by any other means.

This and other objects of the invention will appear from a consideration of the following description of the invention and of the drawing which forms a part thereof, and in which

Fig. 1 is a longitudinal sectional view of a

boiler provided with a fire box embodying this invention;

Fig. 2 is a cross-sectional view of such fire box;

Fig. 3 is a cross-sectional view of another form 5 of fire box embodying this invention; and

Fig. 4 is a fragmentary view in cross section, illustrating still another embodiment.

The boiler 20 includes a fire box 21, a combustion chamber 22, water spaces 23 surrounding the fire box and combustion chamber, a water leg 24 terminating in a crown sheet 25 and a smoke pipe outlet 26. The oil burner (not shown) is placed in the fire box and is accessible and supplied with fuel through the inlet 21. The 15 combustion gases normally flow from the combustion chamber 22, around the end of the crown sheet 25 through flues 28 and 29 to the smoke pipe outlet 26.

The fire box illustrated is made of refractory 20 bricks in the usual manner and is provided with legs 30 by which it is supported upon the bottom of the boiler. Thus there is provided below the fire box a horizontal flue 31 connected by a passage 32 through the water leg 24 to the flue 25 29 opposite the smoke pipe outlet 26. It will be noted that the flue 31 is in contact with the water space at the bottom of the boiler as well as with the water leg 24. A fire box made of metal may be substituted therefor if desired.

In the outer wall of the fire box are formed a plurality of vertical grooves 35 extending from top to bottom of the fire box and providing passages connecting the combustion chamber 22 with the flue 31. Under normal burning conditions the draft will cause the majority of the gases to rise through the chamber 22 and escape through the flues 28 and 29 but a certain fraction of the gases will descend through the passages provided by the grooves 35. When, however, 30 due, for example, to pulsations, the pressures in the fire box arise suddenly, such pressures overcome the normal draft and cause all or a relatively larger portion of the gases to travel down the passages 35 to the flue 31 and thence through the passage 32 to the flue 29 and the outlet 26.

The gases thus escaping give up their heat to those portions of the boiler surface which have heretofore been shielded and inaccessible to hot flue gases such as the water space below the flue 31 and the water leg 24.

Fig. 3 illustrates another form of fire box 40 which differs from that previously described in the type of escape passages provided. The fire box 40 here shown is particularly adapted for use in a boiler of the form shown in the copending

Hannum, Seeley and Desjardins application Serial No. 306,280, filed November 27, 1939. In the outer wall of the fire box 40 are formed vertical grooves 41 which function in the same manner as the grooves 35 to allow the escape of the excess gases. In place of grooves in the fire box, as shown in Figs. 2 and 3, there may be provided grooves 45 in the inner wall of the boiler, as shown in Fig. 4.

The essence of this invention is the provision of passageways through which excess gases may escape to the flue, and while three embodiments of this invention have been shown and described, the invention is not limited thereto and other embodiments may be made without departing from the spirit and scope of the invention as set forth in the following claims.

I claim:

1. In a boiler having a smoke pipe, a fire box, a combustion chamber above said fire box, and flues connecting said combustion chamber with

said smoke pipe and through which gases normally travel, said fire box having grooves in the outer wall thereof, which grooves extend from top to bottom of the fire box and provide passages through which gases may also flow, and a flue below said fire box and connected with said smoke pipe into which said gases are guided by said passages.

2. In a boiler having a smoke pipe, a fire box, 10 a combustion chamber above said fire box, said smoke pipe being located at a level below said combustion chamber, flues connecting said combustion chamber with said smoke pipe and through which gases travel, water spaces 15 rounding the fire box, grooves extending from top to bottom of the fire box between said fire box and said water spaces and forming passages, and a flue below said fire box into which gases flowing through said passages enter, said flue being 20 connected to said smoke pipe.

LAUREN E. SEELEY.
